LESLIE A. D. GARDNER, OF OAKLAND, CALIFORNIA.

DESIGN FOR A COLLAPSIBLE-TUBE CAP.

42,504.

Specification for Design.

Patented May 14, 1912.

Application filed December 22, 1911. Serial No. 667,878. Term of patent 7 years.

● *To all whom it may concern:*

Be it known that I, LESLIE A. D. GARDNER, a citizen of the United States, and residing at Oakland, in the county of Alameda and State of California, have invented a new, original, and ornamental Design for Collapsible-Tube Caps, of which the following is a specification, reference being had to the accompanying drawings, forming a part thereof.

Figure 1, is a side elevation of a collapsi-

ble tube cap, showing my new design. Fig. 2, a top plan view of the same. Fig. 3, an elevation showing an edge view of the loop eye or handle.

I claim:

The ornamental design for a collapsible tube cap, as shown.

LESLIE A. D. GARDNER.
